US0D1114246S

(12) **United States Design Patent** (10) **Patent No.:** **US D1,114,246 S**
(45) **Date of Patent:** **** Feb. 17, 2026**

(54) **ENDOTRACHEAL TUBE**

(71) Applicant: **Samuel Wilson**, South Euclid, OH (US)

(72) Inventor: **Samuel Wilson**, South Euclid, OH (US)

(**) Term: **15 Years**

(21) Appl. No.: **29/971,716**

(22) Filed: **Nov. 5, 2024**

Related U.S. Application Data

(62) Division of application No. 29/734,410, filed on May 12, 2020, now Pat. No. Des. 1,055,275.

CLAIM

The ornamental design for an endotracheal tube as shown and described.

DESCRIPTION

FIG. 1 is a top, front perspective view of an endotracheal tube showing my new design;

FIG. 2 is a bottom, front perspective view thereof;

FIG. 3 is a left view thereof;

FIG. 4 is a right view thereof;

FIG. 5 is a rear view thereof;

FIG. 6 is a front view thereof;

FIG. 7 is a top view thereof; and,

FIG. 8 is a bottom view thereof.

The broken lines shown in FIGS. 1-8 illustrate portions of the endotracheal tube that form no part of the claimed design.

1 Claim, 5 Drawing Sheets
